DESIGN FOR A FLUORESCENT TUBE
SOCKET

René P. Magnenat, Waterbury, Conn.

Application April 9, 1941, Serial No. 100,261

Term of patent 14 years

To all whom it may concern:

Be it known that I, René P. Magnenat, a citizen of the United States, residing at Waterbury, county of New Haven, and State of Connecticut, have invented a new, original, and ornamental Design for Fluorescent Tube Sockets, of which the following is a specification, reference being had to the accompanying drawing, forming part thereof.

Fig. 1 is a front elevational view of a fluorescent tube socket, showing my new design.

Fig. 2 is a rear elevational view of the same.

Fig. 3 is a side elevational view of the same.

Fig. 4 is a top view of the same.

I claim:

The ornamental design for a fluorescent tube socket, as shown.

RENÉ P. MAGNENAT.
